(57) **CLAIM**

The ornamental design for an oval cylinder surveillance
camera and infrared sensor, as shown and described.

DESCRIPTION

FIG. 1 shows a perspective view of an oval cylinder surveillance
camera and infrared sensor;

FIG. 2 shows a front view of the oval cylinder surveillance
camera and infrared sensor of FIG. 1;

FIG. 3 shows a back view of the oval cylinder surveillance
camera and infrared sensor of FIG. 1;

FIG. 4 shows a left view of the oval cylinder surveillance
camera and infrared sensor of FIG. 1;

FIG. 5 shows a right view of the oval cylinder surveillance
camera and infrared sensor of FIG. 1;

FIG. 6 shows a top view of the oval cylinder surveillance
camera and infrared sensor of FIG. 1; and,

FIG. 7 shows a bottom view of the oval cylinder surveillance
camera and infrared sensor of FIG. 1.

The broken lines in drawings FIGS. 1-7 depict portions of
the oval cylinder surveillance camera and infrared sensor
and form no part of the claimed design. There is only one
type of broken lines within the drawings.

1 Claim, 7 Drawing Sheets
